[57] CLAIM

The ornamental design for a floral package, as shown and described.

DESCRIPTION

FIG. 1 is a right front perspective view of a floral package showing my new design,

FIG. 2 is a plan view thereof taken from the underside, and

FIG. 3 is a left rear perspective view thereof.

The broken lines showing flowers in FIG. 1 are for the purpose of showing environmental use only.

FIG. 1
